(57) **CLAIM**

The ornamental design for a trivet, as shown and described.

DESCRIPTION

FIG. 1 is a top perspective view of a trivet of the present disclosure;

FIG. 2 is a bottom perspective view thereof;

FIG. 3 is a top plan view thereof;

FIG. 4 is a bottom plan view thereof;

FIG. 5 is a side elevation view thereof;

FIG. 6 is a second side elevation thereof;

FIG. 7 is a third side elevation thereof;

FIG. 8 is a fourth side elevation thereof;

FIG. 9 is a top perspective view showing the trivet in a compressed position;

FIG. 10 is a top plan view thereof in a compressed position;

FIG. 11 is an upper perspective view thereof in a compressed position; and,

FIG. 12 is a lower perspective view thereof in a compressed position.

The broken lines shown represent the portions of the trivet that form no part of the claimed design.
